LAVATORY FAUCET

Ancil C. Brown, Louisville, Ky., assignor to American Radiator & Standard Sanitary Corporation, New York, N.Y., a corporation of Delaware

Application December 23, 1959, Serial No. 58,773

Term of patent 14 years

(Cl. D91—3)

Fig. 1

Fig. 2

Fig. 3

Fig. 4

Figure 1 is a side elevational view of a lavatory faucet, showing my new design.

Figure 2 is a front elevational view thereof.

Figure 3 is a rear elevational view thereof.

Figure 4 is a top plan view thereof.

I claim:

The ornamental design for a lavatory faucet, substantially as shown.
